William C. Hiering.
By his Attorney, Frank C. Fischer.

UNITED STATES PATENT OFFICE

WILLIAM C. HIERING, OF NEWARK, NEW JERSEY, ASSIGNOR TO J. E. MERGOTT CO.,
OF NEWARK, NEW JERSEY, A CORPORATION OF DELAWARE

BAG-FASTENER CLASP

Application filed April 27, 1925. Serial No. 26,176.

This invention relates to clasp devices applied to the frames of portable containers for retaining them in a normally closed condition.

5 The type of containers referred to include generically, hand bags, pocket books and the like, in which a flexible covering, as leather, is secured at its open upper and end edges, in channelled metal frames, substantially U shaped in cross section, and hingedly connected in pairs at their extremities, the bag material being held between the sides of each pair of channels, filling the space therebetween.

10 15 In common types of securing means one of the fastener elements is engaged with one of the pair of frames to interlock with the mating means on the other frame, such interlocking being accomplished by a spring, the main portion of which is arranged within the channel frame and therefore frequently rendered inoperative by reason of encountering the edges of the covering material, thus failing in the performance of its function by such

20 25 obstruction.

It is therefore one of the main objects of the instant invention to provide a fastener of the snap clasp type in which the spring actuating element is contained almost wholly within the body of the fastener and thus not subject to the "freezing" effect above noted.

30 35 A further feature of this device is in the provision of adequate stops to prevent excessive motion of the movable parts and which normally retains the movable elements in position for engagement with the fixed element.

Another aim is to provide an efficient fastener of simple construction and ornamental 40 appearance, that can be cheaply constructed and readily applied to bags which are otherwise in finished condition.

These and other important features are accomplished by the novel construction and 45 combination of parts hereinafter described and illustrated in the annexed drawing, constituting an essential part of this disclosure, and in which:—

Figure 1 is a partial front elevational view 50 of a conventional type of bag frame, show-

ing an embodiment of the invention as applied.

Figure 2 is a top plan view of the same.

Figure 3 is an enlarged longitudinal sectional view, taken on line 3—3 of Figure 2. 55

Figure 4 is a transverse sectional view taken on line 4—4 of Figure 2, drawn to a further enlarged scale, the open position of the clasp being shown in broken lines.

Figure 5 is a similar sectional view taken 60 on line 5—5 of Figure 2.

Figure 6 is another like sectional view taken on line 6—6 of Figure 2.

Figure 7 is a perspective view of a spring and its holder as used in the construction. 65

Figure 8 is a plan view of the fastener support blank in detail.

Figure 9 is a bottom plan view of the fastener as completely assembled ready for attachment to a bag frame. 70

In common with bags of the class to which the invention is applicable, a pair of frames, respectively designated 10 and 11, are hingedly connected at the extremities of their angular end members, the frame elements 75 being of channel shaped cross section, there being spaces 12 and 13 between the walls of the frame members in which the edges of the bag material are secured.

The clasp, generally designated by the number 14, is composed of a plate having a flat central portion 15, its forward edge being downwardly curved, as at 16, into a reentrant strip 17, disposed at approximately thirty degrees from the plate portion 15 and serving 85 with it as a handle or finger grip for operative purposes.

On the opposite, rear side, the material is bent downwardly at a right angle forming a wall 18, and at the ends of the plate are 90 projections 19, slightly creased at the center of their length, as at 20, this crease being normally in the plane of contact of the frame sides when closed, as best seen in Figure 2.

The rear edges of the extensions are bent 95 to form right angular walls 21, substantially in alignment with the wall 18, and at the front are similar walls 22, their outer surfaces being nearly or quite in register with the corresponding surface of the frame mem- 100

ber 10, over which the plate 15 extends as shown. It will now be seen that the clasp elements, 15 to 22, inclusive constitute in effect a casing for the operative parts about to be described.

5 A pair of lugs 23 reach from the walls 21 inwardly to about the crease 20, adjacent the plate 15, and a single lug 24 extends similarly inward from the wall 22, at the left hand side 10 of the structure, beyond the adjacent lug 23, as best seen in Figure 9.

15 A pair of protrusions 25 are sheared from the frame member 10 and bent to extend perpendicularly from the center as shown in Figure 4, the openings thus produced being normally covered by the overhanging finger grip 17.

20 In the mating frame member 11 are a plurality of openings 26 arranged in paired spaced relation in the curved top of the channel, and a single opening 27 is in alignment therewith, below the right hand extension 19 of the clamp plate.

25 In Figure 8 is shown a support blank, the central longitudinal portion of which is folded to produce a tube 28 from which extend pairs of prongs 29 having angular indentations 30 at their ends facilitating spreading and bending outwardly, after being passed 30 through the openings 26 to be firmly fixed therein, as indicated by the broken lines in Figure 3.

35 On one edge of the central portion of the blank is an extension 31 which is bent and folded upon itself to produce a stop, the end edge of which is seated on the surface of the frame element 11, and the raised curved bight portion presents a surface against which the inner surface of the plate 15 makes contact, 40 preventing excessive movement of the same in a downward direction, the edge of the wall 18 making contact with the exterior of the frame element 11 when the plate is raised to its full extent.

45 It will be obvious that one or more of the stops 31 may be used, if desired, as for instance at the ends of the blank, rather than at the center.

50 A torsion spring 32 passes through the tube 28 and between the lugs 23 and extensions 21, and one of its ends being bent at a right angle 33 to reach under the opposite lug 24 adjacent the wall 22, as at 34.

55 The opposite portion of the spring wire 32 is bent at an angle 35 to extend through the opening 27 in the frame element 11 and then straight out, as at 36, in the bight space 13, as best seen in Figure 3.

60 A catch plate 37 may be proportioned to fit below the plate 15, extending from end to end and from the inside of the curve 16 to make contact with the tube 28, the plate having end extensions 38 reaching between the lugs 23 and elements 19, and between walls 65 22 and spring wire 32, holding the same in

place under the lugs 23, the extensions being conformably shaped for such purpose.

70 In some cases it is desirable to dispense with the plate 37 but when used a recess 39 is formed in its rear edge which permits the stop 31 to pass through, and a pair of openings 40 are provided to receive the protrusions 25, which are entered by merely pressing the frame elements together, the angular element 17, when brought into contact with the protrusions, raising the clasp 14 upon its axis represented by the wire 32, until the protrusions have passed the edge of the element 17 and thereafter engage in the openings 40; when the plate 37 is omitted the protrusions 25 engage the inner edge of the lip element 17 and act to retain the frames closed.

75 It is to be noted that the torsion spring 32 is wholly contained within the body of the clasp, except for its extremity 36, and that this element is held tightly against the inner surface of the channelled frame so as to be unaffected by the bag covering material, irrespective of how firmly it may be packed within the channel.

80 The clasp is obviously released by raising the element 17 manually and simultaneously parting the frame elements, the wall 18 preventing excessive movement, and the stop 31 holding the clasp 14 in position for automatic re-engagement by pressing the bag frame side into intimate contact.

85 As changes of construction could be made within the scope of the invention, it is intended that all matter contained in the foregoing description or shown in the accompanying drawings shall be interpreted as illustrative and not in a limiting sense.

90 Having thus described my invention, what I claim as new and desire to secure by Letters Patent, is:—

95 1. A bag frame clasp comprising a casing fixed on the middle portion of one of the frame members and having a tube wholly enclosed therein, a plurality of prongs extending in paired relation from the tube and rigidly fixed in the mentioned frame side, a torsional spring wire in the tube its ends extending therebeyond, one end of said wire being rigidly held in the casing and the other in the frame side, a projection on the mating frame side over which the casing normally extends level and parallel with the frames, a re-entrantly turned lip on said casing to engage the projection upon closing the frame sides, and a stop on said tube to limit the rotative movement of said casing by action of said spring wire.

100 2. A bag frame clasp comprising a sheet metal tube, means on the tube for anchorage in one of the frame sides, a torsional spring wire enveloped in said tube, a casing mounted on said wire at the ends of the tube, one end of said wire being bent to engage the casing and the other end bent to engage the frame

side, said casing having its upper element normally disposed in a plane parallel and above the frame tops, projections on the mating frame side over which the casing normally extends, to engage therewith means on said casing limiting its upward movement and means on said tube limiting the downward movement of said casing.

5 3. In combination with a bag frame composed of a pair of hingedly engaged channelled sides, a clasp comprising a casing having end extensions disposed midway in the length of one of the frame sides, a holder in said casing fixed on the frame side, projections on the other frame side, a catch plate fixed in said casing having openings to engage said projections, a torsional spring carried in said holder, one end of said spring being fixed in one of the casing extensions
10 and the other end in the first named frame side below the other casing extension, said spring connecting said casing to the holder and permitting the casing to pivot thereon, said casing being normally level and means
15 on said holder to limit the closing movement imparted by said spring to said casing.

20 4. In combination with bag frame members, a clasp comprising a casing disposed midway the length of one of said frame members, said casing being level when in operative position, a sheet metal tube enclosed centrally in said casing, a plurality of prongs extending in paired relation from said tube, said prongs being of uniform length and having
25 notches in their lower edges to spread in opposite directions to become rigidly fixed in one of the frame sides, a torsional spring extending longitudinally through said tube and having offset protruding ends, one of said
30 ends being rigidly held in said casing and the other end fixed in one of the bag frame members, an upstanding projection carried by the mating frame members, a curved and doubled lip on said tube to contact with the frame
35 to limit its movement, and a re-entrantly turned front extension on said casing engageable with said projection.

40 This specification signed and witnessed
45 this 22nd day of April, 1925.

50 WILLIAM C. HIERING.
